Primary Examiner — Natasha Vujcic*Assistant Examiner* — Gilbert B Ford(74) *Attorney, Agent, or Firm* — Mintz, Levin, Cohn, Ferris, Glovsky and Popeo, P.C.(57) **CLAIM**

The ornamental design for a bubble trap, as shown and described.

DESCRIPTION

FIG. 1 is a top perspective view of a bubble trap of our design wherein the ovoid body is translucent;

FIG. 2 is a bottom perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right side elevational view thereof; and,

FIG. 8 is a left side elevational view thereof.

The broken lines illustrate features of the bubble trap that form no part of the claimed design.
